UNITED STATES PATENT OFFICE.

CHARLES F. WILSON, OF NORTHBIDGE, MASSACHUSETTS, ASSIGNOR TO HIMSELF AND JESSE E. FOLK, OF BROOKLYN, NEW YORK.

IMPROVEMENT IN SPINDLE-STEPS FOR SPINNING-MACHINES.

Specification forming part of Letters Patent No. 135,189, dated January 21, 1873.

To all whom it may concern:

Be it known that I, CHARLES F. WILSON, of Northbridge, in the county of Worcester and State of Massachusetts, have invented a new and useful Improvement in Spindle-Steps, of which the following is a specification:

The invention is an improvement in lubricating devices for spindles of spinning-frames, and has reference to the construction of the case or holder for the spindle-step, as herein-after described.

The accompanying drawing represents a vertical central section of my improved spindle-step.

Similar letters of reference indicate corresponding parts.

A represents the oil reservoir or shell within which my step is placed. B is the step-box, which is made from a solid piece of metal bored out for the step of the spindle, and for the passage of the oil, as seen in the drawing. C is the central orifice or step-bearing of the spindle. The oil is introduced into the reservoir through the orifice D. E is a lip, made in punching the orifice, against which the tube of the oil-can will strike instead of striking the spindle. F F are holes bored from the top of the step-box to a point a little below the bottom of the spindle-orifice C. G is a hole bored horizontally into the box, so as to connect with the holes F F, as seen in the drawing. From this hole a small hole, H, is bored to the center of the spindle-orifice C. The step of the spindle is beveled to an angle of about

forty-five degrees, so that the oil which is forced up through the small hole H readily spreads and perfectly lubricates the extreme end of the spindle.

The oil-reservoir may contain more or less oil; it may be filled to near the orifice D, so that the step of the spindle will always run in oil. The top of the oil-reservoir is turned in around the spindle, as seen at I, so as to exclude lint and dust.

The step-box is confined in the bottom of the shell A, and the latter is confined in whole in the rail, so as to correspond in position with the spindle-bolster in the rail above.

The spindle is seen in dotted lines in the drawing.

Having thus described my invention, I claim as new and desire to secure by Letters Patent—

1. In a spindle-lubricating device, a sheet-metal case or cover, A, having its oil-hole formed by punching back a portion of the case, substantially as and for the purpose specified.

2. A spindle-lubricating device formed of the sheet-metal case or shell A, bent inward at the top, and inclosing the step-block B, provided with holes G, H, and F, for passage of the oil, all constructed and arranged as shown and described, for the purpose specified.

CHARLES F. WILSON.
